Attorney

UNITED STATES PATENT OFFICE

RALPH WOODRUFF PAYNE, OF WASHINGTON, DISTRICT OF COLUMBIA, ASSIGNOR TO
THE RAIL JOINT COMPANY, OF NEW YORK, N. Y., A CORPORATION OF NEW YORK

INSULATED RAIL JOINT

Application filed April 28, 1930. Serial No. 448,129.

This invention relates to rail joint structures, and particularly to an improvement therein having special utility in connection with rail joints of the insulated type employed in connection with track signalling systems.

To that end, the invention has in view a simple and practical joint construction wherein provision is made for an adjustment that effectively keeps the joint parts in a properly tightened relation, and also exerts a clamping force on the rails in a direction to obtain a maximum efficiency and life from the insulating material. Also it is an object of the invention to provide a rail joint construction which is particularly applicable to that type of railroad rail now known as the headfree rail wherein the bottom corners of the rail head are truncated, and anchorages for the head of the joint bars are provided at and within the head fillets of the rail.

With these and other objects in view which will be appreciated by those familiar with the art, the invention consists in the novel construction, combination and arrangement of parts hereinafter more fully described, illustrated and claimed, and while the invention is susceptible of structural change without departure from the spirit and scope of the appended claims, a preferred and practical embodiment is illustrated in the accompanying drawings, wherein:

Figure 1 is a cross-sectional view of a rail joint embodying the features of improvement contemplated by the present invention;

Figure 2 is a detail sectional view illustrating a modified form of bevelled washer that may be employed as a part of the joint fastening; and

Figure 3 is a similar view of another form of a bevelled washer that may be utilized in carrying forward the present invention.

Like references designate corresponding parts in the several figures of the drawings.

In carrying forward the present invention

it is especially applicable to the headfree type of railroad rail, which type of rail is covered by the patent to Thomson, No. 1,507,870 dated September 9, 1924, and involves as a characteristic feature thereof a rail head 2 having the bottom corners truncated as at 3, thereby substantially eliminating the usual flat fishing surface of the under sides of the head of the rail, and producing curved joint bar seats or anchorages 4 at or within the head fillets of the rail so that the loading engagement of the joint bars is at the head fillets of the rail.

In a rail of the type referred to, it is desirable to provide a proper fitting and adjustment for the joint bars in order to maintain the permanent loading engagement of the bars at the head fillets of the rail, and in the case of insulated joints to provide for maintaining the efficiency and prolonging the life of the insulating material for a rail of this type. To that end the novel joint structure constituting the present invention includes, at each side of the rail, a joint bar designated generally by the reference letter 5 having an inclined web portion 6 provided at its outer side with the inclined downwardly and outwardly sloping clamping face 7, and at its upper edge with a head portion 7^a the characteristic feature of which is the rounded bearing member 8 fitting the head fillet 4 of the rail, or the head insulating material 9 interposed between the same and the rail. In addition to these features, the joint bar 5 is formed with a foot portion 10 overlying the rail flange and preferably formed with the integral base member 11 underlying the rail flange in the manner of the well known continuous-type rail joint bar.

To provide for proper adjustment of the inclined joint bar, particularly in the direction to move its head portion inwardly into proper fitting relation to the head fillet of the rail, there is preferably employed an adjustment wedge block 12 arranged at the outer side of each joint bar, and provided

with an inner inclined bearing face 13 and an outer vertical bolting face 14 with which cooperate the heads and nuts of the joint fastening bolts 15.

5 The structure so far described is applicable to a standard or non-insulated joint, but as it possesses special utility in connection with an insulated construction for headfree rail there is shown in Figure 1 of the drawings 10 the necessary insulating equipment. This insulating equipment may consist of the fibre head piece 9 fitting the head fillets of the rail, and provided with downwardly extending skirt portions 15^a alongside of the rail 15 web and upstanding flange portions 16 lying between the head of the bar and the truncated face of the rail head inside of the vertical plane of the outside of the rail head.

In addition to the head insulation 9, the 20 insulating equipment of the joint illustrated includes the base insulation piece 17 underlying the foot of the joint bar and overlying the rail supporting base member 11 thereof, and also the insulating bushings 18 for the 25 joint bolts and the fibre and metal washer plates 19 and 20 respectively associated with the bolt heads and nuts and the vertical bolting faces 14 of the adjustment wedge blocks 12.

30 It will be seen from the construction described that a tightening of the joint fastening bolts causes the adjustment wedge blocks 12 to have a wedging engagement with the inclined clamping faces 7 of the joint bars 35 in such a manner, and exerted in such a direction, that an inward adjustment of the head of the bar is compulsory, thereby maintaining the proper tight fit of the bar head within the head fillet of the rail and against the interposed insulation at that point where 40 the joint is an insulated joint. In connection with the insulated joint phase of the invention, a detail of construction that may be resorted to is the provision of an easement 45 groove or depression 21 formed in the head of the bar opposite the outer terminus of the rail head fillet 4. This feature provides for the easement of pressure on the insulating material at this point, thus reducing the risk 50 of more quickly cutting out here than at other points within the joint.

In carrying out the invention it may be found desirable to introduce a spring tension in the joint fastening, and that may be accomplished by utilizing an adjustment wedge block 12 of a spring type of construction, such for instance as shown in Figures 2 and 3 of the drawings. In Figure 2, the spring-type beveled washer 12^a shown may consist of a 60 spring metal plate folded to provide an outer vertical bolting member 22 and inner inclined wedge clamping member 23 having a spring clearance. Or, as shown in Figure 3 of the drawings the beveled clamping washer designated by the reference number 12^b may con-

sist of a spring plate of bowed formation at its inner inclined side 24 and having an outer vertical bolting face 25. In both of these suggested modifications, as well as in the main construction shown in Figure 1 the adjustment wedge blocks may be only sufficiently long to accommodate one nut, or may be sufficiently long to accommodate two or more nuts. Also a detailed feature of practical importance, in connection with the action of the wedge blocks 12 is preferably to provide or form on the outer inclined face of the joint bar a stop bead or projection 26 located in proximity to the tops of the wedge blocks and acting as stops preventing upward displacement of these blocks thereby preventing cutting or damage to the bolt insulation or to the bolt threads.

70 Other modifications of the invention will be apparent without further description, and it is to be understood that various changes in the form, proportion, and minor details of construction may be resorted to, without departing from the spirit of the invention and 75 scope of the appended claims.

80 I claim:—

1. A rail joint including the rail and the joint bar, the joint bar having an outer clamping face inclined downwardly and outwardly from the head to the base of the bar, and a 85 wedge member engaging said face and having an outer bolting face.

2. A rail joint including the rail, a joint bar having loading cooperation at its head with the head fillet of the rail and provided with an outer clamping face inclined downwardly and outwardly from the head to the base of the bar, and a wedge member engaging said face and having an outer vertical bolting face.

90 3. A rail joint including a rail having bar anchorages within the head fillets, and truncations at the bottom corners of its head, a joint bar having a loading engagement in said anchorages, joint insulation including head insulation fitting said anchorages and truncations, and wedge adjusting means for the bar.

100 4. A rail joint including a rail of the head-free type, a joint bar having a loading engagement with the head fillet of the rail and an easement depression in its head opposite the outer terminus of the rail head fillet, and insulation interposed between the rail and said bar.

105 5. A rail joint including a rail having head fillets and truncations at the bottom corners of its head, a joint bar formed at the upper inner corner of its head for loading cooperation with a head fillet of the rail, and a head piece of insulation disposed between the upper inner corner of the joint bar and the related head fillet of the rail and extending into the space provided by the adjacent truncation of the bottom corner of the rail head.

6. A rail joint including the rail, and the joint bar, the joint bar having an outer clamping face inclined downwardly and outwardly from the head to the base of the bar, a wedge member engaging said face and having an outer bolting face, and a stop formation on the outer face of the joint bar to limit upward movement of the wedge member relative to the joint bar.

10 In testimony whereof I hereunto affix my signature.

RALPH WOODRUFF PAYNE.
